UNITED STATES PATENT OFFICE.

ROLLIN H. WHITE, OF CLEVELAND HEIGHTS VILLAGE, OHIO, ASSIGNOR TO THE
WHITE COMPANY, OF CLEVELAND, OHIO, A CORPORATION OF OHIO.

PLURAL-CYLINDER ENGINE.

1,103,639.

Specification of Letters Patent.

Patented July 14, 1914.

Application filed March 6, 1912. Serial No. 681,955.

To all whom it may concern:

Be it known that I, ROLLIN H. WHITE, a citizen of the United States, residing at Cleveland Heights Village, in the county of 5 Cuyahoga and State of Ohio, have invented a certain new and useful Improvement in Plural-Cylinder Engines, of which the following is a full, clear, and exact description.

10 The primary object of this invention is to reduce the weight, the size, and the cost of plural cylinder internal combustion engines of the V-type, without reducing their efficiency; to do away with puppet valves, and 15 to provide suitable means for lubricating the valve mechanism.

The invention involves the employment of a single casting which includes the cylinders, the exhaust manifold and the valve 20 casings,—said manifold and valve casings being disposed within the V-space between the two rows of cylinders,—and water circulating space which surrounds the cylinders, the exhaust manifold, and the valve 25 casings. This construction and combination of parts, and other subordinate combinations of parts which contribute to the efficiency of the engine, constitute the improvements which are defined by the appended claims; and said invention in the 30 best form known to me is shown in the accompanying drawings and hereinafter fully described.

In the drawing, Figure 1 is a side elevation, partly broken away and sectioned, 35 of an engine embodying this invention. Fig. 2 is a front end view of said engine with the valve driving mechanism sectioned. Fig. 3 is a vertical transverse section in the plane indicated by line 3—3 on Fig. 1. Fig. 4 is a plan view of the engine when the 40 cap plate is removed, and some of the parts sectioned. Fig. 5 is a sectional plan view in the plane of line 5—5 on Fig. 3. Fig. 6 is a sectional plan of somewhat more than one-half the engine in the plane indicated by 45 line 6—6 on Fig. 3.

The engine shown has six cylinders; but, 50 obviously, the invention is capable of being embodied in an engine having any even number of cylinders. The engine is what is known as the V type; that is to say, the cylinders are arranged in two rows. The three cylinders A', A⁵, A³ in one row have their axes in the same inclined plane; and the

three cylinders A⁴, A², A⁶ in the other row have their axes in another inclined plane; and said planes intersect at the axis of the crank shaft. In a six cylinder engine these planes lie at an angle of 30 degrees to each other, and at angles of 15 degrees to a vertical plane which passes through the axis of the crank shaft.

The cylinders are cast *en bloc*; that is to say, all six cylinders are part of the same 65 casting, which casting also includes the valve casings B, B', the exhaust manifold C, and cored out water spaces which surround the cylinders, the exhaust manifold and the valve casings. Each of the cylinders A', A⁵, A³, has near its top a port a, which leads to the valve casing B. Each of the cylinders A⁴, A², A⁶, in the other row has near its top a port a' which leads to the valve casing B'. Associated with each of 75 these ports a, a' is an inlet port a² which leads from the associated valve casing through the top of the casting, so as to communicate with the inlet manifold f which is a space or chamber between the top of 80 the casting and a cap plate F which is removably secured to the top of said casting. Associated with each of the ports a, a' is also an exhaust port a³ which leads from the associated valve casing to the exhaust manifold C. 85

Suitable valves, which will be subsequently described in detail, are provided for controlling the flow of gas from the inlet manifold to the several cylinders, and from 90 the several cylinders to the exhaust manifold. That is to say, the ports a, a' of the several cylinders will be connected with the associated inlet ports a² during the suction strokes of the pistons in the associated cylinders. Said ports a, a' will also be connected with the associated exhaust ports a³ during the scavenging strokes of the piston in the several cylinders. Said ports will be closed completely during the compression 95 and explosion strokes of the piston. 100

The exhaust manifold C referred to is a tube which is an integral part of the same casting in which the cylinders are formed. This tube is located in the V-shaped space between the two rows of cylinders. An exhaust pipe C' is connected with the rear end of the casting over the otherwise open rear end of the exhaust manifold. 105

Within the casting are cored out water 110

jacketing spaces H which surround the exhaust manifold and the several cylinders and the valve casings. Water is delivered to these water circulating spaces from a tube h, which lies within and near the bottom of the V-shaped space between the two rows of cylinders, and is an integral part of the casting. The front end of this tube projects forward so as to permit the attachment of a water supply pipe, and its open rear end lies near the rear end of the casting. The discharge outlet for the cooling water is through a hole h' in the top of the casting and near the front end thereof. The cooling water, therefore, enters the pipe h and is discharged into the water circulating space within the casting near the rear end thereof, and flows upward and forward and is finally discharged through the hole h'. The cap plate F is formed with an integral tube f' whose open bottom registers with the hole h' when the cap plate is secured in position.

Any suitable valves and valve operating mechanism may be employed with the construction thus far described. But, since it is desired to avoid the use of puppet valves, the construction shown in the drawings has been devised. Two cylindrical valve casings B, B' are formed as integral parts of the casting, in the V-shaped space between the two rows of cylinders, but in a plane above the exhaust manifold. They extend from one end of the casting to the other, and the rear ends of these valve casings are closed by a cap plate J. In these cylindrical valve casings the two cylindrical valves E, E' are rotatably mounted and nicely fitted. The surface of the valve E is cut away or grooved at three points, e¹, e², e³. The length of these grooves measured lengthwise of the valve, is such as corresponds with the lengths of the ports a, a², a³. The extent of these grooves, measured circumferentially, is such that during about one-quarter of the revolution of the valve communication will be established through each groove between the associated port a and the associated inlet port a². For approximately another quarter of the revolution communication will be established through each groove between the associated port a and exhaust port a³. During the remainder of the revolution there will be no communication between the port a and either of the ports a², a³.

The valve E', which is fitted in the valve casing B' is substantially like the valve E, as described, in that it has three grooves e⁵ for co-operation with the associated groups of ports a', a², a³. These two valves E, E' revolve at one-half the crank shaft speed, and are so set that the several cylinders will be connected with the inlet manifold in the order indicated by the exponent figures

applied to the reference letter A. These valves are driven from the crank shaft P by means of a vertical shaft K which has a lower bearing M, through which it passes into the crank case G. It has an upper bearing m' through which it passes into a housing m², which is an integral part of the casting. This housing has a removable cap m³. The worm gears e, e' are fixed respectively to the front ends of the two rotatable valves E, E'. A worm k on the upper end of the shaft K engages with these two worm gears. A worm gear k' on the lower end of the shaft K is connected by means of a train of gears n, n' and n² with the crank shaft P, to which the last named gear is fixed.

The two valves E and E' have, because of the worm and worm gear driving mechanism, a tendency to move endwise in opposite directions. The end thrust of the valve E is taken up at the rear end by bearing against an adjustable screw R. The end thrust of the valve E' is borne by an adjustable screw R'. In order to lubricate this valve mechanism oil is discharged through pipes S, S, into an annular space b' between the rear ends of these valves and the plate J, within the rear ends of the two valve casings. Each of the valves has a hole e² extending longitudinally through it from one end practically to the other end. Diagonal holes e⁴ lead from the central longitudinal hole in these valves to the space b', and it is through these longitudinal holes that oil, delivered into the space b' will flow through the valves to the front end thereof, and that oil will be discharged from the front end of the valves into the housing m². From this housing the oil will flow down between the shaft K and its upper bearing (said shaft having a spiral groove) into a tube T, which embraces the shaft and extends from the upper to the lower bearing, and from this tube the oil will flow between the shaft (which has a spiral groove) and its lower bearing into the crank case.

Each of the valves E, E' has several radial ducts e⁴ leading from the central hole e² therein to the surface, and it is through these ducts that oil will be discharged to lubricate the engaging surfaces, between the valves and the valve casings.

The crank shaft P has three cranks p which are set at 120° apart and they are connected in any suitable or well known manner with the several pistons of the several cylinders; that is to say, one crank will be connected with the pistons and the two associated cylinders one in each row.

The inlet manifold f between the cap plate F and the top of the engine will be connected with any suitable carbureting apparatus by means of the mixture inlet pipe Q.

The foregoing is a description of the spe- 130

cific construction which is shown in the drawing, and no attempt has been made to catalogue the various changes which obviously may be made therein without departure from the invention which is defined by the appended claims.

Having described my invention, I claim:

1. In a plural cylinder engine, the combination with a single casting in which are formed two rows of cylinders disposed V-wise, an exhaust manifold which is in the V space between the two rows of cylinders, valve casings which are also located in the V space between the two rows of cylinders, and water circulating spaces which surround the cylinders, the exhaust manifold and the valve casings,—there being a port leading from each cylinder to its associated valve casing, an inlet port associated with each cylinder leading from the associated valve casing through the top of the casting, and a port associated with each cylinder leading from the associated valve casing to the exhaust manifold, of a removable cap secured to the top of the casting thereby inclosing an inlet manifold.

2. In a plural cylinder engine, the combination of a single casting in which is formed two rows of cylinders disposed V-wise, an exhaust manifold which is in the V space between the two rows of cylinders, valve casings which are also located in the V space between the two rows of cylinders, a water inlet tube which is formed in the V space between said cylinders and has an open front end, and is extended nearly to the rear end of the casting and is open at its rear end, and cored out water circulating spaces with which the rear end of said water inlet tube discharges, which water spaces surround the cylinders, the exhaust manifold and the valve casings and has a water discharging hole at the top of the casting near its front end, of a removable cap secured to the top of the casting thereby inclosing an inlet manifold, said cap being formed with a water discharge tube which registers with said water discharge hole in the casting when the cap is in place.

3. In a plural cylinder engine, the combination of a single casting in which is formed two rows of cylinders disposed V-wise, an exhaust manifold which is in the V space between the two cylinders, two longitudinally extended cylindrical valve casings which are located in the V space between the cylinders and above the exhaust manifold,—there being a port leading from each cylinder to the adjacent valve casing, and an inlet port associated with each cylinder leading from the associated valve casing through the top of the casting to the inlet manifold, and an exhaust port associating with each cylinder leading from the associated valve casing to the exhaust manifold, and there

being also within the casting water circulating spaces which surround the cylinders the exhaust manifold and the valve casings, of two valves rotatably mounted in said two valve casings, each valve having in its surface grooves located at places such that each groove coöperates with a group of three ports associated with a cylinder, means for rotating said valves, and a removable cap secured to the top of the casting, thereby inclosing an inlet manifold.

4. In a plural cylinder engine, the combination of a single casting in which is formed two rows of cylinders disposed V-wise, an exhaust manifold which is in the V-space between the two cylinders, two longitudinally extended cylindrical valve casings which are located in the V space between the cylinders and above the exhaust manifold,—there being a port leading from each cylinder to the adjacent valve casing, and an inlet port associated with each cylinder leading from the associated valve casing through the top of the casting to the inlet manifold, and an exhaust port associating with each cylinder leading from the associated valve casing to the exhaust manifold, and there being also within the casting water circulating spaces which surround the cylinders, the exhaust manifold and the valve casings, of two valves rotatably mounted in said two valve casings, each valve having its surface grooves located at places such that each groove coöperates with a group of three ports associated with a cylinder, means for rotating said valves, each of said valves having a hole extended through it from end to end and having lateral ducts leading from said hole outward, means for discharging oil into the rear ends of said valve casings, and means for conducting the oil from the front ends of said valve casings to a suitable reservoir therefor.

5. In a plural cylinder engine, the combination of two rows of cylinders disposed V-wise, two cylindrical valve casings arranged in the V-shaped space between the two rows of cylinders, there being ports connecting the cylinders of one row with one of said valve casings, and there being also ports connecting the cylinders of the other row with the other valve casing, an inlet manifold common to all of the cylinders disposed within the V-shaped space between the two rows of cylinders, said inlet manifold being connected with each of the valve casings by as many ports as there are cylinders connected with said valve casing, an exhaust manifold common to all of the cylinders, which exhaust manifold is connected with the two valve casings by as many ports as there are cylinders connected with each valve casing, a rotary valve in each valve casing having surface grooves through which communication will be made from

each cylinder to the inlet manifold and from each cylinder to the exhaust manifold.

6. In a plural cylinder engine, the combination with a row of cylinders, an inlet 5 manifold, an exhaust manifold and a tubular valve casing disposed at the side of the row of cylinders and between the exhaust manifold and the inlet manifold, there being a port leading from each cylinder to said 10 valve casing, an inlet port associated with each cylinder leading from the valve casing to the inlet manifold, and an exhaust port associated with each cylinder leading from the valve casing to the exhaust manifold, a rotatable cylindrical valve mounted in said 15 valve casing and having as many surface grooves as there are cylinders, each groove being located in a position to coöperate with the three ports associated with a cylinder, 20 said valve being tubular and having a plurality of ducts leading from the hollow center to the surface of said valve, means for discharging oil into one end of the valve casing, means for conducting the oil from 25 the other end of the valve casing to a suitable receptacle therefor, and means for rotating said valve.

7. In a plural cylinder engine, the combination with a row of cylinders, an inlet 30 manifold, an exhaust manifold and a tubular valve casing disposed at the side of the row of cylinders and between the exhaust manifold and the inlet manifold, there being

a port leading from each cylinder to said valve casing, an inlet port associated with each cylinder leading from the valve casing to the inlet manifold, an exhaust port associated with each cylinder leading from the valve casing to the exhaust manifold, a rotatable cylindrical valve mounted in said valve casing and having as many surface grooves as there are cylinders, each groove being located in a position to coöperate with the three ports associated with a cylinder, 35 said valve being tubular and having a plurality of ducts leading from the hollow center to the surface of said valve, means for discharging oil into one end of the valve casing, a vertical shaft mounted in two bearings supported by the front end of said casting, a tube loosely embracing the vertical shaft and extending from the upper to the lower bearings thereof, a housing over the upper end of said shaft and front ends of the valves, a worm fixed to the upper end 40 of said shaft, and worm gears meshing therewith fixed respectively to the front ends of said valves, and mechanism transmitting motion from the engine crank shaft to said vertical shaft.

In testimony whereof, I hereunto affix my signature in the presence of two witnesses.

ROLLIN H. WHITE.
